J. F. Heinkel,
Attorney

UNITED STATES PATENT OFFICE

FRIEDERICH W. LIEBCHEN, OF CLEVELAND, OHIO, ASSIGNOR TO BESSIE GOLDBERG, OF CLEVELAND, OHIO

DRAPEY-HOLDING DEVICE

Application filed June 6, 1927. Serial No. 196,936.

My invention relates to devices which enable draperies or similar objects or portions thereof to be held in useful and ornamental positions.

One of the objects of my invention is to provide a simple, inexpensive, easily operable, easily installable, and easily removable device which does not blemish or stain or in any manner effect or change the natural color or material of draperies nor causes permanent creases or wrinkles or other deformities in draperies. Other objects will appear, or become apparent or obvious, or will suggest themselves during the following description of the apparatus or device shown in the accompanying drawing.

In order to illustrate my invention, I have embodied the same in a certain device shown in the accompanying drawing in which

Fig. 1 is a perspective view of a portion of a window with a shade and a drapery hung thereon and a drapery holding device of my invention holding the lower portion of the drapery toward one side of the window.

Fig. 2 is a perspective view, on a larger scale, of the drapery holding element of Fig. 1 fastened directly to the frame of the window.

Fig. 3 is a perspective view of the bracket element which may or may not be used with the element shown in Fig. 2.

Fig. 4 is a sectional perspective view showing a bracket element on the edge of the window frame and one holding element inserted into the bracket in three positions; one position is shown in full lines and the other positions are shown in dotted lines.

Fig. 5 is a sectional perspective view showing a bracket element on the face of the window frame and one holding element inserted in the bracket in four positions; one position is shown in full lines and the other positions are shown in dotted lines.

Similar reference characters refer to similar parts throughout the views.

In the present instance, the holding element (Fig. 2) is made of one piece of material, band iron in the present instance, bent into an angular supporting member comprising the tongues or portions 10 and 11 at an angle with each other and each having the holes 12 through the same for screws or nails to fasten the holding element directly to the window frame, the lip member 13 to prevent shifting of the holding element in the bracket (hereinafter described), the member 14 angular with the portion 11 to offset the loop portion (hereinafter described) from the window frame for such purposes as clearing the window shade, and the oblong loop member A comprising the portion 15 angular to the member 14, the portion 16 closing one of the shorter sides of the loop A, the portion 17 substantially parallel with the portion 15, and the portion 18 partly closing the other one of the shorter sides of the loop A and defining an outwardly curved drapery confining portion and an inwardly curved drapery retaining portion and an outwardly curved drapery leading portion and leaving the open neck 19 between the end of the portion 18 and the member 14 so that this neck is located near the supporting portion of the holding element and near one of shorter sides of the loop A and angular with one of the longer sides of the loop A.

In the present instance, the bracket B (Fig. 3) is made of one piece of material and comprises the flat portion 20, the doubled up portion 21, and the doubled up portion 22 offset from the portion 20 to provide the space 23 into which portions of the holding element can be inserted. The holes 24 are provided therein for screws or nails to fasten the bracket to the window frame.

The supporting members 10 and 11 of the holding element can be fastened directly onto the edge and the face of the window frame by means of screws or nails through the holes therein as seen in Fig. 2.

The bracket B can be fastened either to the edge of the window frame as seen in Fig. 4 or to the face of the window frame as seen in Fig. 5 by means of screws or nails through the holes therein.

5 When the holding element is in position, a portion of the drapery 25 is manually inserted into the loop A through the neck 19, is gathered in the loop A, and is retained in the loop A by the portion 18 since the neck 19 opens from one side of one of the longer sides of the loop and does not open endwise so that the drapery can not leave the loop until it is manually moved and guided out of the loop through the neck.

10 The holding element is painted or laquered or otherwise coated to enhance the appearance of the device and to prevent oxidation or other action or other changeable condition 20 of the material of the holding element from injuring or blemishing or tarnishing or otherwise detrimentally affecting draperies. The fringe element C, shown in Fig. 1, has the loop portion 26 telescopicable over the 25 outer longer side of the loop A and the ornamental fringes 27 depending from the portion 26. The element C can be used for the same purpose as the painting of the holding element.

15 30 When the holding element is fastened to the edge of the window frame, as seen in Fig. 2, the portions 10 and 11 retain the holding element in position and a portion of the drapery can be inserted into or removed from 35 the loop A thereof through the neck 19. The resiliency of the free end of the portion 17, aided by the round end thereof, prevents injury to the drapery during the insertion or removal thereof into and from the loop.

35 40 When the bracket B is fastened to the edge of the window frame as seen in Fig. 4, or when it is fastened to the face of the window frame as seen in Fig. 5, the holding element can be inserted therein in various ways or positions; seven different positions being indicated in Figs. 4 and 5.

45 In any of the ways of insertion of the holding element into the bracket, the walls 20 and 22 of the bracket retain the holding element 50 in position in one direction and the lip 23 or the portions 10 or 11 or 14 retain the holding element in another direction since they are all angular to each other and abut a surface of the bracket adjacent to the slot 23 in 55 any of the positions.

The holding element can be used either as a unit in itself or in combination with the bracket as desired.

60 This combination of the bracket and the holding element permits the holding element to be removed entirely when so desired and leaves practically no obstruction on the window frame since the bracket is made very thin so that it does not project sufficiently far from 65 the window frame to present any serious dis-

advantage; this combination also permits the holder element to retain or hold a drapery in a variety of positions.

I am aware that changes can be made in the form of the elements as well as in the arrangement thereof shown and described; therefore, without limiting myself to the precise form or structure nor to the precise arrangement thereof as shown and described, I claim:—

70 1. A device of the character described including a holder element and an oblong loop member having an open neck adjacent to one of the short sides thereof; said one short side being curved to normally prevent a drapery from leaving said loop member.

75 2. A device of the character described including a holder element and a supporting member and an oblong loop member having an open neck adjacent to one of the short sides thereof; said loop member being offset from 80 said supporting member; said one short side being curved to normally prevent a drapery from leaving said loop member.

85 3. A device of the character described including a supporting bracket made of sheet material with a portion thereof doubled up against another portion thereof and a portion of said doubled up portion spaced from said other portion and a holder element having a member insertable into the space between 90 said portions of the supporting bracket.

95 4. A holding element of the character described formed of one piece of material bent into supporting seats angular with each other, an offset portion adjacent to said seats, and a 100 loop portion angular to said offset portion.

105 5. A holding element of the character described formed of one piece of material bent into supporting seats angular with each other, an offset portion adjacent to said seats, 110 and a loop portion angular to said offset portion and having an open neck at the beginning of said loop portion and the end of said offset portion.

115 6. A device of the character described including a supporting bracket and a hold back for a drapery; said bracket adapted to be fixed to a support and having a receiving slot and said hold back having a portion thereof adapted to be selectively inserted into and removed from said slot and thereby permit said hold back to be installed or removed from said bracket independently of said drapery and of other parts of the device.

120 7. A device of the character described including a supporting bracket and a hold back for a drapery; said bracket adapted to be fixed to a support and having a receiving slot and said hold back having a plurality of portions angular with each other and each portion adapted to be selectively inserted into and removed from said slot and thereby permit said hold back to be installed on said bracket in different positions as well as to be removed from said bracket from any of the different 125 130

positions independently of said drapery and of other parts of the device.

8. A device of the character described including a supporting bracket and a drapery hold back; said bracket adapted to be fixed to a support and having a receiving slot and said drapery hold back including an oblong drapery holding loop having a drapery confining portion and a drapery retaining portion and an open neck at one of the sides of said loop and a portion adapted to be selectively inserted into or removed from said slot and thereby permit said drapery hold back to be selectively installed on or removed from said bracket.

9. A device of the character described including a supporting bracket and a drapery hold back; said bracket adapted to be fixed on a support and having a receiving slot and said drapery hold back including an oblong holding loop having a curtain confining portion and a curtain retaining portion and an open neck at one of the sides of said loop and a plurality of portions angular with each other and each adapted to be selectively inserted into or removed from said slot and thereby permit said drapery hold back to be selectively installed on said bracket in different positions or to be removed from said bracket from any of the positions thereof.

10. A device of the character described including a positionally fixable bracket, a holding element, and an interengaging tongue and slot means whereby said holding element is supported on said bracket.

11. A device of the character described including a positionally fixable bracket having a slot therein and a holding element having a member adapted to be inserted into said slot and thereby support said holding element on said bracket.

12. A device of the character described including a positionally fixable bracket having a slot therein and a holding element having members angular with each other and each adapted to be inserted into said slot and thereby support said holding element on said bracket in different angular relations to said bracket.

13. A device of the character described including a bracket and a holding element suspendable on said bracket and having a loop member adapted to confine a drapery therein and an open neck to provide an exit and an entrance for said drapery from and into said loop member and positioned so that said drapery can not normally leave said loop member through said open neck.

14. A device of the character described including a bracket and a holding element suspendable on said bracket and having a loop member adapted to confine a drapery therein and an open neck to provide an exit and an entrance for said drapery from and into said loop member and positioned so that said

drapery can not normally leave said loop member through said open neck; said loop member having a drapery leading portion adjacent to said neck.

15. A device of the character described including a bracket formed of sheet material with a slot between portions thereof and a holding element having a tongue adapted to be inserted into said slot and thereby support the same on said bracket.

In the testimony of the foregoing I affix my signature.

FRIEDERICH W. LIEBCHEN.
